SHUTTLE THREADING AND TENSION MECHANISM

Filed April 3, 1942

Fig. 1.

UNITED STATES PATENT OFFICE

2,324,949

SHUTTLE THREADING AND TENSION
MECHANISM

Luigi Pavia, Allentown, Pa.

Application April 3, 1942, Serial No. 437,532

6 Claims. (Cl. 139—223)

This invention relates to shuttles, and more particularly to shuttles of the automatic threading type having tension and take-up mechanism. Shutties of this type are particularly designed for use in looms using extremely fine weft or filling which normally has a strong tendency to kink or snarl if it is allowed to become slack in the shuttle member during the weaving process.

An object of the invention is to provide a self-threading shuttle which at all times will tension the thread but will allow its free movement through the shuttle.

In the accompanying drawing—

Fig. 1 is a plan view of a shuttle embodying my invention;

Fig. 2 is a detail view partly in cross-section showing the thread-tensioning means;

Fig. 3 is a cross-sectional view taken on the line 3—3 of Fig. 2;

Fig. 4 is a cross-sectional view taken on the line 4—4 of Fig. 2;

Fig. 5 is a detail view of the outside of the shuttle eye.

The shuttle 10 is of the conventional type having a bobbin or quill 11 engaged by clamping means 12 and some soft material (such as fur) 13. My invention lies in the threading and tensioning mechanism mounted in a recess 14 in the forward part of the shuttle. The thread 15 passes from the quill through the thread passage 16 in which is mounted tensioning means 17 consisting of two spring-pressed bearings which prevent the thread from snarling as it leaves the quill due to slackness. A threading slot or groove 20 is provided in the outer end of the shuttle and a cover plate 21 covers the recess 14 and is held in place by the screw 22 as well as by parts of the mechanism which will be described later. The cover plate 21 has a point 23 which frictionally engages the side 24 of the groove 20. The plate 21 also has a depending lug or guide 25 and has mounted therein a guide wire 26.

Mounted on the pin 30 is a guide wire bent upon itself to form a bearing 31 and having one end 32 and one loop 33 positioned in the notch 34. For the purposes of description the entire guide will be identified by the numeral 35. It will be seen that in view of the pin 30 and the notch 34, this guide is fixed and is not free to move.

Mounted on the pin 40 is another guide made of wire bent upon itself to form the loop 41 which is in turn bent upon itself to form a thread-guiding loop 42. At the end of the coil 43 an arm 45 ex-

tends into the recess 26 and is engaged by a rubber band 47 fastened to the pin 43. Instead of the rubber band 47, any suitable tensioning means may be used.

At the side portion of the shoulder is the eye section 50. A post 51 is provided as a guide and an eye 52 is provided by bending wire in the form of a loop 53 with an upstanding guide post 54 at one end and a U-shaped guide 55 terminating in the end 56 which is imbedded in the shuttle to position the mechanism.

In threading the shuttle, the thread 15 is brought out into the threading groove 20 between the open top of the guide 17, is led through the space between the point 23 and the groove 20, and is then brought rearwardly along the passage 60 around the post 54, looped around the guide 55 into the eye 52. While this is what appears from the exterior of the shuttle, the fact is that the thread is guided by the post 61 through the loop 42 across the guide 35 through the eye 52.

The post 61 is mounted in the plate 21 and engages a recess 63 in the shuttle. A recess 64 is also provided in the shuttle to position the guide 26. As the thread is moved through the passage 60, the guide 26 and the guide 35 position it so that it must go into the loop 42. Due to the action of the tension means 47, the loop 42 has a yieldingly downward pull and the operation is resisted by the tension of the thread being drawn through it. This will prevent any back-lash of the thread or any snarling when the drawing of the thread ceases, but will allow the thread to run freely when the shuttle is operated. When the loop 42 is in the downward position the end 41 thereof is positioned in the recess 65 in the bottom of the plate 21.

I claim:

40. 1. In a self-threading shuttle having a shuttle body with a forwardly extending thread passage formed therein and a lateral delivery passage, in combination, a fixed guide means and tension member pivoted at its forward end and having a laterally extending arm and an elastic member engaging said arm adapted to yieldingly position the rear end of said tension member in a downward position.

2. A shuttle having a forward extending thread 50 passage and a chamber in the forward part of said shuttle, a plate mounted over said chamber, a guide post on said plate adjacent said thread passage, a depending guide on said plate, a fixed guide member in said chamber sloping rearwardly, a pivoted loop guide member in the forward

part of said chamber having a laterally extended arm, and elastic means engaging said arm.

3. A self-threading shuttle including a chamber at its forward end, a plate over said chamber said plate having a depending lug, an eye positioned adjacent said chamber, said eye comprising a piece of wire fastened at one end to the forward portion of said shuttle bent upon itself to form a guide and having the other end bent inwardly upon itself to form the eye and engaging a recess in said plate.

4. A shuttle having a forwardly extending thread passage and a chamber in the forward part of said shuttle communicating with said thread passage, a plate covering said chamber, a depending guide post on said plate adjacent said thread passage, a depending sloping guide on said plate, a fixed guide member having a plurality of arms sloping rearwardly in said chamber, a pivoted loop guide member mounted in the forward part of said chamber and extending rearwardly, said pivoted loop guide member being adapted to cooperate with said fixed guide member to tension said thread, said pivoted loop guide member having an arm extended laterally, and elastic means engaging said arm adapted to

yieldingly hold said pivoted loop guide member in a rearward position.

5. In a shuttle having a chamber in the forward part thereof, tension means, said tension means including a fixed guide member having a plurality of sections sloping rearwardly and downwardly, a pivoted loop guide member mounted in the forward part of said chamber having a laterally extending arm, elastic means tending to tension said loop guide member downwardly around and between said fixed guide member, and an eye in the side of said shuttle adjacent said guide members for the passage of thread.

6. A shuttle having a chamber in its forward end and a thread passage to said chamber, said chamber having a sloping side wall, an eye in said side wall, tensioning means in said chamber, said tensioning means including stationary guide means and a pivoted loop member having a laterally extending arm, elastic means tensioning said loop means, a plate covering said chamber, fixed guide members on said plate, and a depending lug on said plate forming with said sloping side wall of said chamber a thread passage leading to said eye.

LUIGI PAVIA.
